(57) **CLAIM**

The ornamental design for a tray for a self-service parcel terminal, as shown and described.

DESCRIPTION

FIG. 1 is a front perspective view of a tray for self-service parcel terminal. The broken line represents designation of enlargement shown in FIG. 2.

FIG. 2 is a front perspective view detail thereof.

FIG. 3 is a back perspective view thereof. The broken line represents designation of enlargement shown in FIG. 4.

FIG. 4 is a back perspective view detail thereof.

FIG. 5 is a front side elevation view thereof. The broken line represents designation of enlargement shown in FIG. 6. Cross-sectional view taken along line 13-13 is shown in FIG. 13.

FIG. 6 is a front side elevation view detail thereof.

FIG. 7 is a back side elevation view. The broken line represents designation of enlargement shown in FIG. 8.

FIG. 8 is a back side elevation view detail thereof.

FIG. 9 is a right/left side elevation view thereof. The broken line represents designation of enlargement shown in FIG. 10.

FIG. 10 is a right/left side elevation view detail thereof.

FIG. 11 is a top/bottom plan view thereof. The broken line represents designation of enlargement shown in FIG. 12.

FIG. 12 is a top/bottom plan view detail thereof.

FIG. 13 is a cross-sectional view taken in the direction of line 13-13 of FIG. 5. The broken line represents designation of enlargement shown in FIG. 14; and,

FIG. 14 is a cross-sectional view thereof.

In the drawings, the broken lines represent enlarged view designations that form no part of the claim. In FIG. 5, the two broken line arrows represent a sectional designation that forms no part thereof.

1 Claim, 11 Drawing Sheets
